UNITED STATES PATENT OFFICE.

LOUIS A. CASGRAIN, OF BEVERLY, MASSACHUSETTS, ASSIGNOR TO UNITED SHOE MACHINERY COMPANY, OF PATERSON, NEW JERSEY, A CORPORATION OF NEW JERSEY.

SHOE-SUPPORT.

1,122,240.

Specification of Letters Patent.

Patented Dec. 22, 1914.

Application filed March 14, 1912. Serial No. 683,759.

To all whom it may concern:

Be it known that I, LOUIS A. CASGRAIN, a citizen of the United States, residing at Beverly, in the county of Essex and State of Massachusetts have invented certain Improvements in Shoe-Supports, of which the following description, in connection with the accompanying drawings, is a specification, like reference characters on the drawings indicating like parts in the several figures.

This invention relates to shoe supports and has for its object to provide a support having improved facilities for presenting the shoe held by it in position to be operated upon.

The invention is herein embodied in a support for holding a lasted and soled shoe in position for the shank to be beaten at each lateral edge downwardly upon the bottom of the last which is at such times within the shoe, the purpose of the operation being to conform the shank of the shoe bottom to the transverse curvature of the last bottom and to compact the materials of the shoe bottom so that in appearance they will present a minimum of thickness. The beating machine illustrated is an adaptation of the machine shown in United States Letters Patent No. 768,560 granted August 23, 1904, on my application and in which the operation of the machine is dependent upon the maintenance of continuous contact between the work and the beating tool. One of the problems to be considered in the contemplated use of a beating machine is the reduction of the transmission of vibration through the shoe and support to the treadle upon which the operator must maintain his foot.

One of the features of this invention is found in the construction and arrangement of the connections between the treadle and the jack spindle. The main features of the invention, however, are found in the shoe holder and the provisions permitting movement of the shoe to present its different parts, particularly the length of the two edges of the shank, to the beater. These features will be better understood in connection with the following description but it may be well here to point out that one of the most important characteristics is the provision for movement of the shoe under the beating tool lengthwise in a curved path which is approximately parallel with the

curvature of the shoe bottom in the shank at either edge and another valuable characteristic of the shoe holder is the provision for the heel clasp and the toe clasp each to turn independently about substantially identical axes that extend lengthwise of the shoe for adaptation of the clasps to the shape of the shoe. These and other features of the invention will now be described in connection with the drawings and then be particularly pointed out in the claims.

Figure 1 is a side elevation of a machine in which this invention is embodied; and Fig. 1^a is a detail of the treadle connection; Fig. 2 is a perspective view of the shoe holder; Fig. 3 is a vertical longitudinal section of the heel clasp; Fig. 4 is a similar section of the toe clasp.

The column or frame has bearings for the jack spindle 2 the lower end of which is sustained by a toggle 4, 5. The member 5 being pivoted to the column at 6 and having a horizontal arm 8 is in effect a bell crank or spindle lifting rocker. Underlying the arm 8 is the arm 9 of a rock shaft 11 the other arm 10 of which overlies the rear arm of treadle 12. A spring 15 approximately balances the weight of the jack while a stop 13 limits the extent to which the spindle may be pressed down when a shoe on its last is placed in the holder. The described leverage between the treadle and the spindle affords ample advantage for holding the shoe up to the pounding tool 100 which is rapidly reciprocated from a rotary actuator as described in United States Letters Patent No. 768,560, and at the same time said leverage connections absorb the vibrations of the shoe holder sufficiently so that there is not an objectionable motion of the treadle upon which the operator must hold his foot while a shoe is being pounded. A spring 16 is confined on the spindle between collars 17, 18, the latter of which is adjustable to vary the compression of the spring. Upon the upper end of the spindle is a bracket the arms 21 of which support the edges of a table 20 and through a large hole in the top of the table depends the stem 23 of a float 25, the stem carrying a foot plate 24 larger than the hole in the table and free to slide around against the under side of the table in a recess 22 as appears in Fig. 1. This affords provision for free turning and also horizontal sliding movements of the

shoe holder upon the table within the limits of the hole in the table. The float has rollers 26, 27, 26 between which is confined and guided the arc-shaped foot 30 of the 5 shoe holder, the same being curved substantially parallel with the curvature of the shank, see Fig. 1, of a standard shape of last so that the beating point on the shank is maintained in approximately the same 10 vertical relation to tool 100 as the beating progresses along the shank.

The heel clasp post 32 is secured upon one end of the foot 30 and the toe clasp post 40 upon the other end, each post being made 15 adjustable for the length of the shoe. The heel clasp comprises a back plate 34 having a horizontal stem 35 which is confined but free to turn in a socket in the post. On its lower edge the back plate is formed as an 20 arc curved about the stem and rests on a similarly curved shelf formed on the front side of the post to assist in sustaining the weight of the heel clasp and the shoe so that the stem 35 can turn freely. Wing blocks or 25 plates 36 are confined in a transverse guideway in the front face of the plate by a cap 38. The forwardly extending padded wings of these blocks 36, which are downwardly and inwardly inclined to form a seat for the 30 heel constitute the heel sustaining members of the shoe holder and they are adjustable from and toward each other by the screw rod 39 for wide and narrow shoes.

The toe post 40 has on the rear side an 35 arc-shaped guide rib curved about an axis substantially corresponding with the stem 35 and on which slides a block 42 in which is clamped for vertical adjustment the stem of a toe rest 45 that has limited turning movement on its stem about a transverse pivot 40. The toe post also pivotally supports at 45 the toe abutment 50 which has a thickly padded back face and is movable in a direction to engage over the toe end of a shoe 45 and clamp it down upon the toe rest with sufficient security to retain the shoe firmly in the holder. A handle lever 52 is pivoted on the front side of the abutment by which to lift it into clamping engagement with the toe of the shoe and a spring pressed pawl 54 on the abutment is arranged to engage ratchet teeth in the toe block to lock the abutment in operative position. The head of the pawl is located under the handle lever 52, downward pressure upon which first lifts the point of the pawl and then swings the abutment to free the shoe. The weight of the handle lever holds the point of the pawl normally raised but the pivot for the 55 pawl is so located that after the abutment has been clamped down upon the toe by the use of the lever 52 the pawl spring causes the pawl to engage the ratchet teeth and the pressure caused by the reaction of the 60 work maintains the engagement after the 65

handle has been released. A spring 56 returns the abutment to an upraised position after the shoe has been removed. The location of the pivotal connection between the abutment 50 and the toe post 40 is such that 70 the abutment can clamp shoes of several sizes without resorting to adjustment of the toe post or the heel post on the foot 30.

In the use contemplated in the drawings a lasted and soled shoe, with the last in it, 75 will be dropped into the heel clasp, pushed back, and then pressed down upon the toe rest, the abutment being swung aside for this latter purpose. The handle 52 will then be lifted to clamp the abutment against 80 the toe of the shoe, the direction of movement of the abutment serving to clamp the shoe backwardly into the heel clasp as well as downwardly upon the toe rest and the pawl 54 will lock the abutment while the 85 handle is upraised. While the shoe is being applied to the holder the holder will have occupied a position on table 20 most 90 remote from the tool 100. The holder will now be moved across toward the tool and the treadle pressed down to lift the shoe into the field of action of the tool 100 and maintain it there. The operator then tips the shoe by a movement of the foot 30 in 95 its guide 26, 27, 26 and slides the holder on table 20 to present one side of the shank to the tool and then turns the holder around on the table and similarly presents the other side of the shank. Downward pressure on handle 52 will release pawl 54 and 100 tip back the abutment to allow the shoe to be removed. The connections between the spindle 2 and the treadle 12 prevent objectionable jarring of the treadle by reason of the vibration of the tool.

Having described my invention, what I claim as new and desire to secure by Letters Patent of the United States is:

1. In a shoe support, a spindle, a treadle, 110 a rock shaft having two arms one of which is engaged by the treadle, and a toggle comprising one member connected to the spindle and a second member connected to the first one and fulcrumed on a fixed support and having a lateral arm in position to be lifted by the second rock shaft arm.

2. In a shoe support, a spindle, a treadle, 115 and a vibration absorbing connection between the treadle and spindle comprising a spindle lifting rocker, and a rock shaft having one arm arranged to engage an arm of the rocker and the other arm arranged to be engaged by the treadle.

3. In a shoe support, a spindle, a treadle, 120 and a vibration absorbing connection between the treadle and spindle comprising a spindle lifting rocker, a rock shaft having one arm arranged to engage an arm of the rocker and the other arm arranged to be engaged by the treadle, a spring partially to 125 130

counterbalance the weight of the spindle and work, and an adjustable stop to limit the descent of the lifter against the spring.

4. In a shoe support, a spindle, a bracket on the end of the spindle having radial arms, a table supported on the arms and having a central aperture, a float mounted to slide freely on the top of said table and having a stem extending through said aperture, a foot plate located between the arms and the lower face of the table and secured to the stem to confine the float on the table, and a shoe holder on the float.

5. In a shoe support, a spindle, a table, a float horizontally movable freely over the table, a shoe holder having an arc-shaped foot with its curvature in a vertical plane about a center above the shoe, and means on the table for guiding said foot for endwise movement in said vertical plane.

6. In a shoe support, a table, a float movable horizontally on the table, a shoe holder, and interlocking guiding means between the float and shoe holder arranged to direct movement of the holder in a vertical plane and in a path curved in parallelism to the curvature of the shank of a shoe in the holder.

7. In a shoe support, a shoe holder having a foot comprising a bar vertically curved about a center located above a shoe positioned in said holder and in parallelism with the longitudinal curvature of the shank of the shoe, and a support in which the bar is confined and guided for endwise movement in the direction of the curvature of the bar.

8. In a shoe support, a shoe holder comprising a foot bar curved lengthwise in parallelism with the curvature of the shank of a shoe located in the holder, sustaining means permitting movement of the foot in the direction of said curvature and also in a horizontal plane, a heel clasp post on one end of the foot, a toe clasp post on the other end of the foot, and a heel clasp and a toe clasp on said posts respectively.

9. In a shoe support, a heel clasp post having a back-plate supported thereon for movement about an axis extending lengthwise of the shoe, and wing blocks attached to the back plate and inclined downwardly and inwardly to embrace and sustain the heel portion of a shoe.

55 10. In a shoe support, a heel clasp post having a back plate supported thereon for movement about an axis extending lengthwise of the shoe, and wing blocks relatively adjustable on the back plate transversely of the shoe to adapt them to hold shoes of different sizes.

11. In a shoe support, a heel clasp post, a back plate, an axial connection between the plate and post extending lengthwise of the shoe, said back plate having an edge

surface curved about said axis, a supporting face formed on the back post for said edge surface, and shoe sustaining means on the back plate.

12. In a shoe support, a toe rest post, a toe end block, interlocking guiding connections formed in said post and block and curved transversely of the shoe, said connections being freely movable relatively to provide movement of the shoe about an axis located in the shoe to be rested, and a toe rest carried by the block and pivoted to be tipped by pressure of the shoe about an axis extending transversely of the shoe.

13. In a shoe support, a toe rest post, a toe end block, freely movable interlocking guiding connections formed in said post and block and curved transversely of the shoe about an axis located in the shoe to be rested, a toe rest stem vertically adjustable in the block, and a toe rest thereon.

14. In a shoe support, a toe rest post, a toe rest carried by the post and a toe end abutment also carried by the post and movable thereon from and into a position to engage the end of the toe and extend over and down upon the toe of the shoe to hold it upon the rest.

15. In a shoe support, a toe rest post, a toe rest carried by the post, a toe end abutment also carried by the post, means by which the abutment can be moved to engage against the end and over the bottom of the toe and clamp it down upon the toe rest, and a locking device to maintain said abutment in holding position over the end of the toe where it will clamp the toe down upon the toe rest.

16. In a shoe support, a toe rest post, a toe rest carried by the post, a toe end abutment pivotally connected to the post below the shoe for movement over against and downwardly upon the toe, a handle lever pivoted on the front side of the abutment by which to lift it into clamping engagement with the toe of the shoe, and a spring pressed pawl on the abutment adapted to engage the post to lock the abutment, the tail of said pawl being located under the lever to receive disengaging movement therefrom.

17. In a shoe support, a shoe holder comprising toe and heel clasps each movable about an axis extending lengthwise of the shoe to allow the shoe to be tipped transversely in the holder, and means in which the holder is sustained and guided for movement in an arc of the curvature of the shank of the shoe.

18. In a shoe support, a shoe holder comprising toe and heel clasps and supports for each clasp in which the clasp is movable independently of the other clasp about the same axis extending lengthwise of the shoe sustained in the holder.

19. In a shoe support, a heel clasp comprising a back plate located at the rear of the heel portion of the shoe, wing plates extending longitudinally of the shoe forwardly from said back plate to embrace the rear portion of a shoe and adjustable transversely of the last from and toward each other on the back plate for widths of lasts, and means for effecting such adjustment.
- 10 20. In a shoe support, a heel clasp comprising a back plate located at the rear of the heel portion of the shoe, wing plates extending longitudinally of the shoe forwardly from said back plate to embrace the

rear portion of a shoe and adjustable transversely of the last from and toward each other on the back plate for widths of lasts, means for effecting such adjustment, and means permitting adjustment of the wing plates together transversely of the last and securing them in adjusted position.

In testimony whereof I have signed my name to this specification in the presence of two subscribing witnesses.

LOUIS A. CASGRAIN.
